US00D491950S1

(12) **United States Design Patent** (10) Patent No.: **US D491,950 S**
(45) Date of Patent: **** Jun. 22, 2004**

(54) **MULTI-FUNCTION SCANNER**

(75) Inventors: **Ronald J. Perry**, Webster, NY (US);
Devin G. Cooper, Fairport, NY (US);
Benjamin Zombeck, Pittsford, NY
(US)

(73) Assignee: **Eastman Kodak Company**, Rochester,
NY (US)

(**) Term: **14 Years**

(21) Appl. No.: **29/181,930**

(22) Filed: **May 16, 2003**

(51) LOC (7) Cl. **14-02**

(52) U.S. Cl. **D14/424**

(58) Field of Search **D14/420-425;**
D18/50, 53-55; 358/474-498

(57) **CLAIM**

The ornamental design for multi-function scanner, as shown and described.

DESCRIPTION

Reference is made to commonly-assigned copending U.S. patent application Ser. No. 09/618,739, filed Jul. 18, 2000, entitled Document Scanning System with Dockable Platen Flatbed Providing Sheet Fed and Platen Scanning Functions, by Westcott et al. and U.S. patent application Ser. No. 10/143,276, filed May 10, 2002, entitled Document Scanning System with Dockable Platen Flatbed Providing Sheet Fed Platen Scanning Functions, by Westcott et al.

FIG. 1 is a front perspective view of the base unit of the scanner with the feed tray and the collection tray in the up position.

FIG. 2 is a rear perspective view of the base unit of the scanner with the feed tray and collection tray in the up position.

FIG. 3 is a front view of the base unit of the scanner with the feed tray in the up position.

FIG. 4 is a rear view of the base unit of the scanner with the collection tray in the up position.

FIG. 5 is a top view of the base unit of the scanner with the feed tray and collection tray in the up position.

FIG. 6 is a bottom view of the base unit of the scanner with the feed tray and collection tray in the up position.

FIG. 7 is a right side view of the base unit of the scanner with the feed tray and collection tray in up position.

FIG. 8 is a left side view of the base unit of the scanner with the feed tray and collection tray in the up position.

FIG. 9 is a front perspective view with the feed tray and the collection tray in the down position.

FIG. 10 is a rear perspective view with the feed tray and collection tray in the down position.

FIG. 11 is a front view of the base unit of the scanner with the feed tray in the down position.

FIG. 12 is a rear view of the base unit of the scanner with the collection tray in the down position.

FIG. 13 is a top view of the base unit of the scanner with the feed tray and the collection tray in the down position.

FIG. 14 is a bottom view of the base unit of the scanner with the feed tray and the collection tray in the down position.

FIG. 15 is a right side view of the base unit of the scanner with the feed tray and the collection tray in the down position.

FIG. 16 is a left side view of the base unit of the scanner with the feed tray and the collection tray in the down position.

FIG. 17 is a front perspective view with the detachable flatbed scanner attached.

FIG. 18 is a rear perspective view with the detachable flatbed scanner attached.

FIG. 19 is a rear view with the detachable flatbed scanner attached.

FIG. 20 is a front view with the detachable flatbed scanner attached.

FIG. 21 is a top view with the detachable flatbed scanner attached.

FIG. 22 is a bottom view with the detachable flatbed scanner attached.

FIG. 23 is a right side view with the detachable flatbed scanner attached.

FIG. 24 is a left side view with the detachable flatbed scanner attached.

FIG. 25 is a rear perspective view of the flatbed scanner.

FIG. 26 is a rear perspective view of the flatbed scanner.

FIG. 27 is a front view of the flatbed scanner.

FIG. 28 is a rear view of the flatbed scanner.

FIG. 29 is a top view of the flatbed scanner.

FIG. 30 is a bottom view of the flatbed scanner.

FIG. 31 is a left side view of the flatbed scanner; and,

FIG. 32 is a right side view of the flatbed scanner.

The claimed design is directed to the appearance of the multi-function scanner as depicted in FIGS. 17–24. The base unit of the scanner with the feed tray and collection tray in the up and down positions illustrated in FIGS. 1–16 along with the flatbed scanner illustrated in FIGS. 25–32 are shown separately for the purposes of disclosing aspects of the design that may not be apparent in FIGS. 17–24.
